UNITED STATES PATENT OFFICE

128,292

DESIGN FOR A LENS SURFACING MACHINE

Albert L. Simonds, Southbridge, Mass.

Application March 10, 1941, Serial No. 99,462

Term of patent 14 years

To all whom it may concern:

Be it known that I, Albert L. Simonds, a citizen of the United States, residing at Southbridge, in the county of Worcester and State of Massachusetts, have invented a new, original, and ornamental Design for Lens Surfacing Machine, of which the following is a specification, reference being had to the accompanying drawings, forming part thereof.

Fig. 1 is a plan view of a lens surfacing machine, showing my new design;

Fig. 2 is a fragmental side elevational view with portions of the article broken away and taken from the front in Fig. 1.

Fig. 3 is a rear elevational view, taken from the right in Fig. 1; and

Fig. 4 is a front elevational view, taken from the left in Fig. 1.

I claim:

The ornamental design for a lens surfacing machine, as shown.

ALBERT L. SIMONDS.
